[57] **ABSTRACT**

Method and apparatus for transferring full yarn packages from a textile machine such as an open-end spinning machine which is provided with a conveyer for discharging full yarn packages doffed from each operation unit, to a carrying device. The carrying attitude of the full yarn packages is corrected while the yarn packages are being carried by the conveyer. At the discharge terminal portion of the conveyer, each yarn package is temporarily held at a predetermined correct position directly above the container chamber of a carrying device and then dropped into the container chamber.

**METHOD AND APPARATUS FOR TRANSFERRING
YARN PACKAGES FROM A TEXTILE MACHINE
TO A CARRYING DEVICE**

SUMMARY OF THE INVENTION

The present invention relates to a method and apparatus for transferring yarn packages from a textile machine to a carrying device, and more particularly to a method and apparatus for transferring yarn packages from a textile machine provided with a conveying means, to a carrying device.

In a textile machine provided with a conveying means such as an endless conveyer mounted along the lengthwise direction of the machine, it is well known that the yarn packages carried to an end of the conveyer are transferred to a carrying device directly or through a chute such as a sliding plate. However, in the above-mentioned transferring method, the yarn packages tend to pile up in a disorderly fashion in the carrying device, because generally there are no means for correcting the condition of the yarn packages which occurs during transfer. The yarn packages also tend to be displaced by their moments of inertia. Consequently, the handling efficiency of the yarn packages in the subsequent process is significantly decreased.

The principal object of the present invention is to eliminate the above-mentioned undesirable feature of the conventional transferring method and apparatus.

Another object of the present invention is to provide an automatic yarn package-transferring apparatus.

To attain these objects, in the present invention related to the textile machinery provided with a conveyer means, the position of the yarn packages carried by the conveying means is corrected during transportation toward the carrying terminal of the conveyer means. The yarn packages are then temporarily held by positioning means, in a position directly above the carrying device. Thereafter, the yarn packages are dropped into the carrying device upon release of packages by the positioning means.

According to the present invention, the above-mentioned transferring method is carried out by an automatic apparatus which is capable of handling a plurality of textile machines, each provided with the novel conveyer means.

BRIEF EXPLANATION OF DRAWINGS

FIG. 1 is a schematic side view of an open-end spinning machine provided with a conveyer belt;

FIG. 2 is a schematic elevational view of a stationary, transferring apparatus mounted on an open-end spinning machine, according to the present invention;

FIG. 3 is a schematic plan view of the transferring apparatus shown in FIG. 2;

FIG. 4 is a schematic side view of the transferring apparatus shown in FIG. 3;

FIG. 5 is a schematic elevational view in partial section of an automatic transferring apparatus and a carrying device according to the present invention;

FIG. 6 is a schematic side view of the transferring apparatus shown in FIG. 5;

FIGS. 7A and 7B are schematic diagrams showing the relative arrangement of textile machineries together with the above-mentioned automatic transferring apparatus shown in FIG. 5, respectively;

FIG. 7C is a schematic diagram showing the relative arrangement of textile machines together with a modified automatic transferring apparatus.

FIG. 8A is a schematic elevational view of the entire machine provided with the automatic transferring apparatus shown in FIG. 5;

FIGS. 8B, 8C, 8D and 8E are schematic elevational views of the transferring apparatus according to the present invention together with a part of a textile machine:

DETAILED DESCRIPTION OF THE INVENTION

The fully packaged bobbin transferring apparatus according to the present invention is hereinafter explained in detail, as applied to an open-end spinning machine provided with a conveying means. Therefore, before explaining the construction and function of the transferring apparatus, a brief explanation of the open-end spinning apparatus is presented. Referring to FIG.

1, in the open-end spinning machine 1, a yarn delivered from a spinning unit 2 is wound on a bobbin 4 which is driven by a take-up drum 3 and rotatably held by a pair of cradles 5 so as to form a full size yarn package 6. A conveyer belt 7 is disposed at a position between a pair of aligned take-up drums 3 in such a way that the conveyer belt 7 is disposed at an intermediate position between a pair of aligned open-end spinning units 2. When a spinning counter (not shown) mounted on the spinning machine 1 detects the predetermined size of a yarn package just before the preselected full size of the yarn package is reached, an indicating lamp is turned on. Thereafter, an operator prepares a carrying box at a predetermined position adjacent to an end portion of the spinning machine 1 and also prepares fresh bobbins to be mounted on each spinning unit, and other related operations are carried out. And when the above-mentioned spinning counter detects that the size of the yarn package formed in each spinning unit 2 reaches a predetermined full size, the spinning counter issues a signal indicating termination of the unit spinning operation for forming the full yarn package and another lamp is turned on by this signal issuing from the spinning counter. The operator can then confirm the termination of the unit spinning operation, and the doffing operation for removing the full yarn package from the cradle 5 of each spinning unit 2, to the conveyer belt 7 is carried out by the operator; thereafter, fresh bobbins are manually mounted on the respective cradles 5 to continue the spinning operation.

The conveyer belt 7, is cleaned by means of a cleaning device comprising a brush 8 and a nozzle 9 (FIG. 2), and is driven prior to the above-mentioned doffing operation. The doffing operation may be carried out by utilizing as an automatic doffing apparatus, an apparatus such as that disclosed in pending patent applications Ser. No. 460,086 and 443,958.

Referring to FIGS. 2 and 3, the yarn packages 6 transferred to the conveyer belt 7 are carried to an end portion of the conveyer belt 7, and then transferred to a carrying device 20 by way of a device for temporarily positioning the yarn package 6. This positioning device is hereinafter represented by reference numeral 10. The positioning device 10 is mounted on the spinning machine 1 at a position directly above the position where the carrying device 20 is positioned. When the yarn packages 6 are transferred on the conveyer belt 7 from the spinning units by the doffing operation, these

yarn packages 6 are haphazardly placed on the conveyor belt 7; however, the disorderly arrangement of these yarn packages 6 is corrected by means of a correction guide 11 disposed at a position above the carrying passage of the conveyor belt 7. In the embodiment shown in FIGS. 2 and 3, the correction guide 11 is provided with a guide surface inclined in the carrying direction so as to permit passage of a yarn package 6 in a standing position on the conveyor belt 7. In the open-end spinning machine 1, the diameter of full yarn package is sufficiently larger than the length of the bobbin 4. Therefore, the upright holding position is the most stable.

A plate 12 covers an end portion of the conveyor belt 7 as shown in FIG. 2. This plate 12 extends to a position adjacent to the positioning device 10, therefore, the yarn package 6 carried by the conveyor belt 7 is transferred to the plate 12 after passing below the correction guide 11. The plate 12 is provided with a pair of upright guide plates 13 formed at both lengthwise edges thereof. Therefore, the yarn package 6 is capable of sliding on the plate 12 along the guide plates 13.

The positioning device 10 is provided with a yarn package receiving member 14 which is capable of temporarily receiving a yarn package 6 from the above-mentioned plate 12. The package receiving member 14 comprises a pair of receiving plates 15a and 15b which are rotatably held by the supporting pins 16a and 16b which are stationarily mounted on the positioning device 10. The shapes of the plates 15a and 15b are identical and each is provided with a semicircular cut-out portion so as to form a round aperture when they are respectively horizontally positioned. The size or diameter of the above-mentioned round aperture is so designed that an end of the bobbin 4 of the yarn package 6 can be freely engaged therein. Therefore, when a yarn package 6 is transferred from the plate 12 to the horizontally positioned receiving plates 15a and 15b of the package receiving member 14, the yarn package 6 can be held at a holding position defined by the above-mentioned round aperture. Therefore, even though the size of the yarn package 6 may vary, all yarn packages 6 can be positioned at the above-mentioned holding position. The sliding motion of the yarn package 6 from the plate 12 to the package receiving member 14 is created by a moment of inertia due to the carrying motion of the conveyor belt 7. The package receiving member 14 is provided with a photodetector 17 (FIG. 4) comprising a light projector 17a and a photocell 17b which receives the light from the light projector 17a (FIG. 3). They are positioned so as to create a light beam from the projector 17a to the photocell 17b, the path of the beam passing just above the horizontal receiving plates 15a and 15b. Therefore, when the light beam is interrupted by a yarn package 6 held by the receiving plates 15a and 15b, the photocell 17b issues a signal.

Referring to FIG. 4, a solenoid 18 is rigidly mounted on the frame of the package receiving member 14. A T-shaped lever 21 is connected to a plunger 19 of the solenoid 18, and the receiving plate 15a is pin-connected to an end 21a of the T-shaped lever 21 by way of a connecting lever 22a, while the receiving plate 15b is pin-connected to an end 21b of the T-shaped lever 21 by way of a connecting lever 22b. Therefore, when the solenoid 18 is actuated by the signal issued from the photocell 17b, the plunger 19 is pulled up-

ward, so that the receiving plates 15a and 15b are turned from their horizontal position to the respective positions represented by the dot-dash line in FIG. 4, in other words, the receiving plates 15a and 15b are opened. As a result, the yarn package 6 held by the receiving plates 15a and 15b is dropped into the carrying device 20 disposed at a position directly below the positioning device 10. A limit switch 24 is disposed at a position where the T-shaped lever 21 is capable of actuating the switch 24 when the plunger 19 is pulled upward. The limit switch 24 issues an electric signal to de-energize the solenoid 18 so that the receiving plates 15a and 15b are returned to their respective horizontal positions. In above-mentioned embodiment, it is useful to utilize a conventional delay timer switch to delay the actuation of the solenoid 18 after the photocell 17b has issued a signal, in order to create a stable transfer operation of the positioning device 10.

The above-mentioned transfer of a full yarn package 6 to the carrying device 20 is repeated, and when the carrying device 20 is filled with a number of full yarn packages 6, the carrying device 20 is displaced from the position directly below the positioning device 10 and an empty carrying device 20 is placed in the receiving position.

To confirm the number of full yarn packages 6 received by the carrying device 20, a counter (not shown) is mounted on the positioning device 10. The counter is actuated by a signal issued from the photocell 17b at the same that the solenoid 18 is actuated. This counter may also be actuated by a signal issued from the limit switch 24. When the counter indicates that a predetermined number of full yarn packages 6 have been transferred from the conveyor belt 7 to the carrying device 20, the operator manually operates a switch (not shown) which controls a connection circuit between a driving mechanism of the conveyor belt and an electric source, whereby driving of the conveyor belt 7 can be stopped and the carrying device 20 is displaced from the receiving position. Since the above-mentioned transfer operation of the full yarn packages 6 is carried out intermittently, because of the intermittent motion of the receiving plates 15a and 15b, it is useful to place a door (not shown) at a position between the conveyor belt 7 and the positioning device in such a way that the door may open synchronously with the intermittent motion of the positioning device 10. However, in the conventional open-end spinning machine, the time interval between two successive full yarn packages 6 arriving at the positioning device 10 is greater than the time interval between two successive motions of the positioning device 10, so the above-mentioned door may be omitted.

According to our experience, if a low count yarn is produced by the open-end spinning machine, or if a so-called high speed winding operation is carried out, the time required to complete the winding operation for producing a full size yarn package is comparatively short in comparison to winding a fine count yarn. In the above circumstances, it is preferable to mount the above-mentioned positioning device 10 in a stationary manner on each textile machine. However, in the case of producing a high count yarn, or applying low speed winding, or forming a large full yarn package, the time interval between two successive doffing operations becomes so long that it may be preferable to use a dis-

placeable positioning device which can be utilized, as common equipment, for a group of textile machines.

FIGS. 5 and 6 disclose an embodiment of the above-mentioned placeable positioning device together with a carrying device. In these drawings, a pair of track rails 27 are supported by a bracket 28 rigidly mounted on each machine frame of a group of textile machines. A positioning device 29 is provided with a pair of track wheels 30 which are capable of rolling on the track rails 27 so that the positioning device 29 is placeably suspended from the track rails 27 as shown in FIG. 5. A driving motor 31 is mounted on the frame of the positioning device 29, and a shaft 30a of the track wheels 30 is driven by the motor 31 through a gear train composed of a gear 32 mounted on a motor shaft 31a, and gear 33 mounted on the shaft 30a in such a way that the gear 32 meshes with the gear 33. A trolley 34 is supported by the brackets 28 of the group of the textile machines in an arrangement parallel to the rails 27. An electrically conductive roller 35 is mounted on the positioning device 29 in such a way that the roller 35 is in constant contact with an electrode wire 36 disposed in the trolley 34. An electrical control mechanism 37 is disposed in the positioning device 29 and is connected to the roller 35 and to an electric photocell 64 for detecting a textile machine which requires operation and to an electric photocell 71 which confirms the completion of the transferring operation. The mechanism 37 is further connected to a solenoid 18 for actuating the receiving plates 15a and 15b and to a photocell 17b for detecting a full yarn package 6 held at the horizontal position of the receiving plates 15a and 15b. Further connection is made a counter 40 (FIG. 6) for counting the number of yarn packages 6 transferred into the carrying device 20 and to a signal transmission device 41, respectively.

A pair of track rails 42 are mounted on the base floor at a position beside an end of the textile machine 1. The carrying device 20 is provided with a pair of track wheels 43 which are capable of rolling on the rails 42. A driving motor 44 is mounted on the carrying device 20 and the track wheels 43 are driven by a power transmission mechanism comprising a gear train composed of a gear 46 mounted on a motor shaft 44a, and a gear 47 mounted on an intermediate shaft 45, a sprocket wheel driving mechanism composed of a sprocket wheel 48 mounted on the intermediate shaft 45 and a sprocket wheel 49 mounted on a shaft 43a of the track wheels 43 and an endless chain 50 connecting the sprocket wheels 48 and 49. A trolley 51 is disposed in the floor and an electrically conductive roller 52 is mounted on the carrying device 20 in constant contact with the trolley 51. A control box 53 is mounted on the carrying device 20. The control box 53 is connected to limit switches 54 and 55 and the driving motor 44. The carrying device 20 is provided with a container composed of a plurality of chambers 56 separated by separation plates 57 (FIG. 6). Each chamber 56 is provided with a metallic projection 59 which actuates a non-contact type limit switch 58 mounted on the textile machine 1. The carrying device 20 is provided with a rack 61 which is capable of intermittently displacing the chambers 56 by means of engaging with an intermittent driving mechanism 60 mounted on the textile machine 1.

In this embodiment, a counter 62 is mounted on the textile machine so as to detect a predetermined condi-

tion corresponding to the size of the yarn package just prior to attaining the predetermined full size of the yarn package, and a lamp 63 mounted on the machine 1 is lighted by a signal issued from the counter 62. A photocell 64 is mounted on the positioning device 29 at a position facilitating reception of a light beam projected from the lamp 63. A magnetic stopper (not shown) is mounted on the textile machine 1 at a position which allows engagement with a notch (not shown) secured to the frame of the positioning device 10 when the counter 62 issues the above-mentioned signal. The positioning device 10 normally runs along the track rail 27.

However, when the counter 62 issues a signal to stop the positioning device 10 at a correct working position thereof, the lamp directs a light beam toward the passage of the positioning device 10 and the above-mentioned magnetic stopper projects to the passage of the notch of the positioning device 10. And when the photocell 64 of the positioning device 10 receives the light projected from the lamp 63, the control mechanism 37 is actuated by the signal issued from the photocell 64 so that the connection between the motor 31 and the conductive roller 35 is opened. Consequently, the motor 31 is stopped. In this condition, the positioning device 10 moves slightly by its moment of inertia, however, as the above-mentioned magnetic stopper engages with the notch, the positioning device 10 is stopped at a correct working position thereof.

The textile machine 1 is also provided with a stopper 65 (FIG. 6) which is actuated by a magnetic means 66 at a position facilitating contact with a limit switch 54 mounted on the carrier device 20. The magnetic means 66 is actuated by a signal issued from the counter 62, and the stopper 65 projects forward toward the carrying passage of the carrying device 20. The stopper 65 is provided with an engageable piece (not shown) which is capable of engaging with a notch member secured to the frame of the carrying device 20 when the stopper 65 projects forward. Therefore, when the counter 62 issues a signal to stop the carrying device 20, the magnetic means 66 is actuated to project the stopper 65 forward. Therefore, when the limit switch 54 of the carrying device 20 contacts the stopper 65, the control mechanism 53 opens the connection between the motor 44 and the conductive roller 52 so that the driving of the carrying device 20 is stopped. As the engageable piece of the stopper 65 is simultaneously engaged with the notch of the carrying device 20, the carrying device 20 is stopped at the correct working position thereof which is directly below the positioning device 10 which is also stopped at the correct working position thereof. In this condition, the limit switch 58 is actuated by the metallic projection 59, and the intermittent driving mechanism 60 is actuated so as to engage the rack 61. Then, the counter 62 detects the predetermined condition of full yarn packages, and actuates a lamp 75 (behind photocell 72) mounted on the textile machine 1 so as to direct a light beam toward the positioning device 29. A control mechanism 68 is mounted on the textile machine to control the operations of machine 1, which include controlling the driving motor 69 for driving the conveyor belt 7.

A dog driving mechanism 74 is mounted on the textile machine 1 at a position to actuate the limit switch 55 which closes the electrical connection between the motor 44 and the conductive roller 52 by way of the ac-

tion of the control mechanism 53. When the above-mentioned counter 62 issues a signal indicating the completion of a unit winding operation, the motor 69 is driven by the action of the control mechanism 68 which is actuated by the signal issued from the counter 62. When the conveyor belt 7 is driven, the yarn packages 6 doffed from the respective operation units, such as spinning units, are successively displaced to the plate 12 one by one, and then displaced onto the receiving member 14 of the positioning device 29. When the photocell 17b detects that a yarn package 6 is held on the receiving member 14, the receiving plates 15a and 15b (FIG. 6) are opened by the motion of the solenoid 18 which is actuated by a signal issued from the photocell 17b and the yarn package 6 is dropped into the containing chamber 56 of the carrying device 20. A counter 70, disposed in the positioning device 29, is actuated by a signal issued from the photocell 17b when a light beam projected from the light projector 17a toward the photocell 17b is interrupted by a yarn package 6 held on the receiving member 14. When the counter 70 detects that a predetermined number of yarn packages 6 have been dropped into the container chamber 56, the counter 70 issues a signal via the electric control mechanism 37, to a light projector 71 mounted on the positioning device. A photocell 72 is mounted on the textile machine 1 at a position facing the light projector 71 and the photocell 72 is connected to the electric control mechanism 68 which is capable of actuating the intermittent driving mechanism 60. Therefore, when the counter 70 issues a signal, the light projector 71 creates a light beam, whereby the photocell 72 issues an electric signal so that the intermittently driving mechanism 60 is actuated. As a consequence of the driving mechanism 60 being actuated, the carrying device 20 is displaced, and when the metallic projection 59 secured to an outside frame of the next container chamber 57 actuates the limit switch 58, the motion of the driving mechanism 60 is stopped by the action of the control mechanism 68 which was initiated by a signal issued from the limit switch 58. Therefore, the next container chamber 56 is positioned at the correct receiving position thereof, below the positioning device 29. The previously mentioned transferring motion of the yarn packages 6 into the carrying device 20 is successively carried out for container chambers 56 of the carrying device 20, and when the transfer operation to all container chambers 56 is completed, the counter 62 is manually returned to the starting point and lamp 75 is switched off. Consequently, the intermittent driving mechanism 60 is displaced in the textile machine so that mechanism 60 is disengaged from the rack 61, and the dog driving mechanism 74 is operated to drive the carrying device 20. The lamp 75 is lighted by the signal issued from the counter 62. A photocell 76 (FIG. 6) is mounted on the positioning device 29 at a position for receiving the light from the lamp 75, and the photocell in turn, issues a signal to close the electrical connection between the motor 31 and the conductive roller 35 by the action of the control mechanism 37. Therefore, when the counter 62 is operated manually after completion of the previously mentioned transferring operation, the lamp 75 is lighted, so that the photocell 76 issues a signal to drive the motor 31 as mentioned above. Therefore, the positioning device 29 is displaced from the above-mentioned working position to the next textile machine which requires carry-

ing out the yarn package transferring operation along the rails 27. At the same time, the dog driving mechanism 74 is actuated by the signal issued from the counter 62 so that the limit switch 55 actuates the control mechanism 53 in order to close the electrical connection between the motor 44 and the conductive roller 52. Therefore, the carrying device 20 containing a predetermined number of full yarn packages is displaced from the above-mentioned working position to the successive process.

In the above explanation, the construction of the electrical control mechanisms 37, 53 and 68 are not explained. However, it should be understood that a combination of magnetic relays which open or close the electric circuit connecting the electric source and the motor or electric source and actuation means may preferably be used for these control mechanisms. Under these circumstances, the magnetic relays are actuated by a signal from the limit switch or photocell.

In the practical application of the transferring apparatus according to the present invention, there are provided several combinations of the stationary positioning device with the above-mentioned displaceable carrying device, or the above-mentioned displaceable positioning device and the displaceable carrying device. In FIGS. 7A through 7C and FIGS. 8A through 8E, several practical embodiments of the transferring apparatus according to the present invention, are disclosed. That is, in the embodiment shown in FIGS. 7A and 8A, each textile machine 1 is provided with a stationary positioning device 10 mounted on respective machine frames and a common carrying device 20, which has both construction and function similar to the carrying device 20 shown in FIGS. 5 and 6, is utilized for a group of textile machines 1. In the embodiment shown in FIG. 7B, a common displaceable positioning device 10 and a common carrying device 20 which are disclosed in FIGS. 5, 6 and 8C, are utilized for a group of textile machines 1. However, a type of displaceable positioning device 10, which is capable of displacement along a rail disposed on the floor as shown in FIG. 8B, may also be used. In the embodiment shown in FIG. 7C, a modified apparatus comprising a displaceable positioning device provided with a container chamber, is disclosed. The displaceable positioning device 10 is capable of displacement along a guide rail disposed on the floor. Instead of utilizing a carrying device 10, a conveyor belt 80 may be used in such a way that it passes the receiving positions below the working positions of the displaceable positioning device 20 at the respective textile machines 1 as shown in FIGS. 7C and 8D.

As previously explained in detail, according to the present invention, in the textile machine, the positions of the full yarn packages being carried by the conveyor belt, are firstly corrected enroute to the positioning device, and then they are temporarily held at a predetermined position above the container chamber of the carrying device. Therefore, when the yarn packages are dropped into the container chamber of the carrying device, each yarn package is correctly positioned in stable condition in the container chamber even though the size of the yarn packages may vary. Even if the yarn packages are held by pegs secured by the carrying device, the above-mentioned dropping of the yarn packages from the positioning device is helpful to mount the yarn packages on the respective pegs.

what is claimed is:

1. A method for transferring yarn packages doffed from units of a textile machine provided with a discharge conveyer leading to a carrying device disposed at a position below a position close to the outside of a carrying terminal of said discharge conveyer, comprising a first step of correcting the carrying positions of said yarn packages while said yarn packages are being carried to said carrying terminal, a second step of moving said yarn packages on said conveyer to a selected discharge position, temporarily holding said yarn packages at said preselected position and close to the outside of said carrying terminal of said conveyer, said yarn packages being received, one by one, from said discharge conveyer in the correct carrying position, and a third step of dropping said yarn packages into said carrying device.

2. A method for transferring yarn packages from a textile machine into a carrying device according to claim 1, wherein, said second step further comprises the step of supporting a bobbin of said yarn package in substantially upright condition.

3. An apparatus for transferring yarn packages doffed from operation-units of a textile machine, provided with a discharge conveyer leading to a carrying device disposed at a position below a position close to the outside of a carrying terminal of said discharge conveyer, comprising means for correcting the carrying position of yarn packages on said conveyer, means for temporarily positioning said correctly positioned yarn packages received from said conveyer at a position close to the outside of a terminal of said conveyer, means for detecting the existence of a yarn package on said positioning means, said positioning means provided with means for supporting and discharging said yarn package, and an actuation means for operating said supporting and discharging means, said actuation means being actuatable by a control signal issued from said detecting means.

4. An apparatus for transferring yarn packages from a textile machine into a carrying device according to claim 3, further comprising a plate member disposed at a terminal portion of said conveyer, said plate member being provided with a pair of guide plates projected upward from both lengthwise edges thereof to form a conduit shaped guide member.

5. An apparatus for transferring yarn packages from a textile machine into a carrying device according to claim 3, wherein said correcting means comprises a guide member disposed close to and above said conveyer along the carrying passage thereof, the distance between said guide member and said carrying passage being dependent upon the carrying position of said yarn packages.

6. An apparatus for transferring yarn packages from a textile machine into a carrying device according to claim 3, wherein said positioning means is mounted in stationary condition on an end portion of said textile machine.

7. An apparatus for transferring yarn packages from a textile machine into a carrying device according to claim 3, further comprising, in combination, a carrying means displaceable along a guide passage around a group of textile machines, said positioning means being mounted on said carrying means, each of said textile machines provided with a first means for issuing a signal to indicate a request for said supporting means and a second means for issuing a signal to indicate that displacement of said supporting means therefrom can be carried out, said carrying means provided with driving means and control means for actuating and stopping said driving means according to signals from said first and second signal issuing means.

8. An apparatus for transferring yarn packages from a textile machine into a carrying device according to claim 7, wherein said carrying device is automatically displaceable along a guide passage around said group of textile machines, said carrying device being provided with a driving means and control means for actuating or stopping said driving means according to signals issued from said textile machine.

9. An apparatus for transferring yarn packages from a textile machine into a carrying device according to claim 3, wherein said supporting and discharging means of said positioning means comprises a pair of receiving plates swingably mounted on the bottom of said positioning means, each of said receiving plates being provided with a semicircular cut-out portion formed at an edge portion thereof, such that said semicircular cut-out portions of the receiving plates form a round aperture having a diameter larger than the diameter of a bobbin of said yarn package when said receiving plates are closed.

10. An apparatus for transferring yarn packages from a textile machine into a carrying device according to claim 3, wherein said detecting means comprises a light source for creating a light beam and positioned to pass through a support position of a yarn package in said supporting and discharging means, and a photocell for receiving said light beam projected from said light projector.

11. An apparatus for transferring yarn packages from a textile machine into a carrying device according to claim 3, wherein said actuation means of said supporting and discharging means is a solenoid.
